CLAIM

The ornamental design for a counting device for a push-up exercise, as shown and described.

DESCRIPTION

FIG. 1 is a perspective view of an exemplary embodiment of the ornamental design for a counting device for a push-up exercise showing our new design.

FIG. 2 is a front elevational view thereof.

FIG. 3 is a rear elevational view thereof.

FIG. 4 is a left elevational view thereof.

FIG. 5 is a right elevational view thereof.

FIG. 6 is a top plan view thereof; and,

FIG. 7 is a bottom plan view thereof.

Any broken lines which may be shown in the views are for illustrative purposes only, and form no part of the claimed invention.
